RIVET STEM PULLER AND CUTTER

Lucien Paul Mellerio and Basil Pomeroy Cooper,
Leicester, England, assignors to United Shoe
Machinery Corporation, Flemington, N. J., a
corporation of New Jersey

Application June 20, 1944, Serial No. 541,230
In Great Britain November 23, 1943

7 Claims. (Cl. 218—19)

1

This invention is concerned with that class of rivet-setting in which a hollow rivet is upset by being expanded by the head of a mandril of which the shank or stem extends through the rivet from a pulling implement engaging the flange end thereof. Since a mandril may be used but once, an object of the invention is to provide an implement that will first do the upsetting and thereafter sever the mandril adjacent to but outside the flange end of the rivet in such a way as to swage the remnant of the mandril remaining in the rivet. The swaging thus produced will retain the remnant in the rivet where it will serve not only to close the throat of the rivet but also to reinforce the shear strength of the assemblage.

A novel feature of a rivet-setting tool embodying the invention is provided by a combination including one means for upsetting a rivet by pulling a mandril, another means for swaging and severing the mandril between the pulling means and the rivet, and actuating mechanism by which the pulling means and the severing means will be operated successively. As herein illustrated, the actuating mechanism includes a lazy tongs the collapsing movement of which produces the effective movement of the mandril by which its head is pulled into a rivet to do the upsetting. The same lazy tongs carry a striker into engagement with an element of the swaging and severing means which is thereupon actuated by continuing the collapsing movement of the tongs after the upsetting stage is completed. Thus, one collapsing stroke of the tongs first does the upsetting and thereafter does the swaging and the severing.

Referring to the drawings,

Fig. 1 is a plan view of the illustrative tool with part of a lazy-tongs mechanism, which it embodies, broken away and with a pair of swaging cutters, with which the tool is provided, shown in section;

Fig. 2 is a plan view showing the lazy-tongs mechanism, of which part only is shown in Fig. 1;

Fig. 3 is a sectional view taken on the line III—III of Fig. 1;

Fig. 4 is a sectional view taken on the line IV—IV of Fig. 1;

Fig. 5 is a sectional view taken on the line V—V of Fig. 1;

Fig. 6 is a sectional view taken on the line VI—VI of Fig. 1;

Fig. 7 is an elevational view of the two cooperating cutters with which the illustrative tool is provided;

2

Fig. 7a is a detail sectional view taken on the line VIIa—VIIa of Fig. 7;

Fig. 8 is a detail elevational view of part of the lazy-tongs mechanism seen in Fig. 2;

5 Fig. 9 is a detail perspective view, partly in section, showing a rivet, with a severed portion of a mandril therein, which has been set by the use of the illustrative tool;

Fig. 10 is a sectional view of the set rivet shown 10 in Fig. 9;

Fig. 11 is a sectional view of the set rivet shown in Figs. 9 and 10, but with the plane of section at right angles to that of Fig. 10; and

15 Fig. 12 is a sectional view similar to Fig. 10, but showing a set rivet in which the severed end of the portion of the mandril which remains in the rivet does not project outwardly beyond the head of the rivet.

In Figs. 9 to 12 the severed end portion of the 20 mandril is shown conventionalized to a precision of geometric form which may not always be exactly obtained in the severing of a metal mandril although the result will have equivalent effect.

25 The illustrative tool comprises a supporting plate 1 having secured thereto a handle 3 which will be held in one hand by the operator when the tool is manipulated. The plate 1 has projecting therefrom a lug 5 in which is a bore which 30 serves as a guideway in which a rod 7 is slidably mounted. The rod 7 is affixed by screw-threads to a rectangular block 9 (see Figs. 1, 2 and 4). The block 9 has recesses 11 at opposite sides thereof and in these recesses are received rolls 13 mounted 35 on pins 15 carried at the bifurcated end portions of two levers 17 which are pivoted on pins 19 fixedly mounted in lugs 21 formed on the plate 1 (see particularly Fig. 6). At their other end portions the levers 17 have pins 23 fixed in them 40 (see particularly Figs. 1 and 3) which project at each side of the levers. One pin 23 (the uppermost in Fig. 1) is received in slots 25 formed at the end portions of two similar levers 27. The other pin 23 is received in slots 29 formed at the bifurcated end portion of a lever 31. The lever 31 lies between the levers 27 and all three are connected by a pivot pin 33 (see particularly Fig. 8) which has a large head 35 constituting a striker, the purpose of which will be hereinafter described. The levers 27 and 31 have links 37 pivoted to them at their far ends and the links 37 are pivoted together on a pin 39 carried by a knob 41. The levers 17, 27 and 31 and the links 37 50 form a lazy-tongs mechanism by which the rod 7 will be moved in one direction lengthwise of a

55

mandril in consequence of moving the knob 41 in the opposite direction, but the movement of the rod will be relatively short and powerful. The lost-motion connection provided by the pins 23 and slots 25 and 29 enables the levers 27 and 31 to continue their collapsing movement despite stoppage of the levers 17.

The rod 7 has an axial bore 43 therein which is just large enough to receive the stem portion of a mandril M. Mandrels used for this work have stems of sufficient ductility to undergo considerable swaging in the process of being severed by the cutters hereinafter described. When a mandril has been inserted in the bore 43 it can be secured therein by a clamp screw 45 threaded in the rod 7 and having an operating handle 47. The bore 43 in the rod connects with another bore 49 of larger diameter. In the bore 49 is received a plunger 51 which at its right-hand end (Fig. 4) is engaged by one end of a compression spring 53 the other end of which bears against the block 9. As seen in Fig. 4, when the mandril M is inserted in the tool its end engages the plunger 51 and moves the plunger to compress the spring 53. When the clamp screw 45 is loosened, the portion of the mandril remaining in the tool is moved outwardly by the plunger 51 to remove it or permit its ready removal.

The tool is provided with two cutters 55, 57 which swage and sever the stem of the mandril M after the riveting operation. The cutters 55, 57 are respectively held by screws 59 to a pair of jaws provided by levers 61, 63, the cutters having serrated faces 65 which engage similar serrated faces on the jaws to insure that the cutters maintain their positions with respect to the jaws. Referring to Figs. 1 and 5, the lever 61 has formed on it two arcuate flanges 67 which are separated by a sufficient distance to allow clearance between them for the rod 7. The lever 63 has formed on it two similar arcuate flanges 69 which are separated by a greater distance than the flanges 67 and straddle the latter. The lever 61 has at each outer surface thereof (Fig. 5) an arcuate groove 71 and the lever 63 has similar arcuate grooves 73 which are arranged concentrically with the grooves 71. Two plates 75, 77 are provided, one at each side of the levers, and each has a circular rib 79 embedded in one of the grooves 71 and one of the grooves 73. A screw 81 is threaded in one of the flanges 67 and has an unthreaded portion 83 extending through bores in one of the flanges 69, the plate 77 and in the plate 1. The screw 81 has a head 85 received in a counterbored portion of the plate 1. The length of the portion 83 of the screw is sufficient to prevent clamping the parts when the screw is tightened. Another screw 87 is threaded in the other flanges 67 and has an unthreaded portion 89 which extends through bores in the other flanges 69 and in the plate 75. The screw 87 has a head 91 which is received in a counterbored portion of the plate 75. The ribs 79 and grooves 71, 73 provide bearing surfaces permitting relative angular movement of the levers 61 and 63 about an axis perpendicular to the axis of the rod 7.

The free ends of the levers 61, 63 are offset to clear the levers 17 (Fig. 4) and are connected by toggle links 95 and pivot pins 93 and 97, the latter also connecting the knee of the toggle and the yoke 99 of a stem 101 arranged to slide endwise in a bearing 103 which projects from the plate 1. The path of the knee of the toggle is

parallel with the path of the mandril-gripping means. The stem 101 carries a headed screw 105 arranged to be struck and moved by the aforesaid head 35 when the collapsing movement of the lazy tongs is nearly spent. The adjustment of the screw 105 with respect to the stem 101 determines the location of the point of impact at which the head becomes effective to actuate the toggle. A lock nut 107 may be used to maintain adjustment.

Normally the cutters 55, 57 are separated as shown in Figs. 1 and 7 by a tension spring 109 which is stretched between pins 111 on the levers 61 and 63. The separation of the cutters under the action of the spring 109 is limited by the engagement of the right-hand face (Figs. 1 and 4) of the yoke 99 with the left-hand face of the lug 103. Movement of the stem 101 toward the left (as looked at in Figs. 1 and 4) closes the cutters.

The cutters 55, 57 constitute a pair of blunt nippers that swage the mandril stem in the process of severing it. The operative end 115 of the cutter 55 has two angularly related faces which meet to form a point, the angle of the point being about 140° (Fig. 7). The faces 117 of the cutter 57 form a V-shaped trough or notch the vertex 119 of which is flattened off. In Fig. 7a the operative end 115 of the cutter 55 at the locality of the point is of square section but the opposing surface of the cutter 57 is beveled to deflect some of the metal of the mandril toward the rivet. The arrangement is such that when the cutters are brought together the pointed end 115 tends to split the mandril stem by deflecting some of the metal at each side in a direction away from the axis of the stem. Consequently, when the mandril stem is finally severed, the severed end of the portion left in the rivet will be swaged laterally beyond the diameter of the rivet bore. Using cutters of the character described (though it will be realized that other forms of swaging means might be used to give different deforming results) produces a fishtail formation F, the width of the fishtail (Figs. 9 and 10) being appreciably greater than the original diameter of the mandril stem, at the locality of severing, and greater than the diameter of the bore in the rivet.

The construction and arrangement of the elements are such that the lazy-tongs mechanism is effective first to pull the head of a mandril into a rivet and thereafter, but while maintaining the pulling force, to cause operation of the cutters 55, 57. The operation of the cutters is derived from the aforesaid head or striker 35 after the levers 17 have been moved as far as need be to complete the rivet-setting operation. To allow continued movement of the lazy-tongs mechanism while the levers 17 and the rod 7 remain stationary (or substantially so) but maintain the rivet-setting pull, the aforesaid pivot pins 23 are installed in the slots 25 in the levers 27 and in the slot 29 in the lever 31. Normally the pins 23 are maintained at the left-hand ends (as seen in Fig. 1) of their slots by compression springs 121 which are seated at their right-hand ends in the levers 27 and 31, and at their left-hand ends bear against small bearing blocks 123 which are slid able and have incurved surfaces which bear against the rounded ends of the levers 17. Consequently, when the levers 17 are arrested by the resistance encountered, the knob 41 and the head or striker 35 may continue to move toward the left (as looked at in Fig. 2) by

virtue of longitudinal movement of the levers 27 and 31 along the pins 23 as a result of the lost motion afforded by the springs 121 and the pin-and-slot connections. This feature enables the head 35 to engage the screw 105 and thereby operate the cutters 55, 57.

The plate 1 has a lug 125 in which are threaded a stop-screw 127 and a setscrew 129. The tool may, as hereinafter described, be operated in two different manners in one of which the stop-screw 127 is employed and in the other of which it is not. In the latter case it may be removed or screwed to the right (as looked at in Fig. 4) into an inoperative position.

To use the described tool a mandril M with a rivet R thereon will be thrust into the bore 43 in the rod 7 and clamped therein by the screw 45. At this stage the lazy-tongs mechanism will be extended as illustrated in Fig. 2, the rod 7 will be in its extreme left-hand position (as looked at in Fig. 4), and the cutters 55, 57 will be separated to allow the mandril stem to lie between them. Before the mandril stem is clamped it will be moved to the right (as looked at in Fig. 4) until the head of the rivet R contacts with the front faces of the cutters 55, 57 (see Fig. 1). The cutters serve, during the rivet-setting operation, as an anvil to hold the rivet head up to the work while the mandril is being pulled.

Having loaded the tool, the operator will next present the tool to the work (say two sheets of metal to be secured together) which will have already had a hole formed to receive the rivet. The operator will hold the handle 3 of the tool in his left hand, leaving the right hand free to shift the knob 41 of the lazy-tongs mechanism toward the work. It will first be assumed that the stop-screw 127 has been removed or has been adjusted to an inoperative position.

The thrust exerted by the operator against the knob 41 causes the cutters 55, 57 to hold the rivet head firmly against the work. In addition, however, the lazy-tongs mechanism due to movement about pins 19 moves the block 9 and rod 7 toward the right (as looked at in Fig. 4). This serves to pull the head H of the mandril M into the setting end portion of the rivet and thereby to expand that portion of the rivet and draw the expanded metal thereof tightly against the work. The arrangement is such that until the mandril has been pulled sufficiently to complete the upsetting the springs 121 hold the levers 27, 31 so that the pins 23 are at the left-hand ends (as looked at in Fig. 1) of their slots 25, 29. When, however, the mandril has been pulled as far as it can go, the springs 121 will yield to permit the levers 27, 31 and links 37 to continue their collapsing movement despite stoppage of the lever 17. The construction is such that the striker 35 will have approached close to, but not yet struck, the screw 105 at the stage when the mandril is arrested, but eventually the striker will operate the cutters to swage the mandril and sever it adjacent to the head of the rivet. It will be appreciated that in setting a rivet the illustrative tool serves to maintain the rivet-setting pull on the mandril up till the moment when parting of the mandril stem occurs. It will also be appreciated that in the described operation of the tool the maximum pull imparted to the mandril is dependent upon the strength of the springs 121. In setting rivets in work of different thicknesses the mandrels may need to

be moved through different distances but the coming into operation of the cutters occurs only after the striker 35 has advanced far enough to engage the screw 105 which can be adjusted to

5 postpone such engagement until the pulling motion of the mandril is arrested. If desired, the screw 127 may be adjusted to arrest the pulling motion of the mandril instead of depending upon the rivet and the riveted work for that purpose, but in either case the springs 121 will permit and absorb the latter stages of collapsing movement of the levers 27 and 31 during which the toggle links 95 will be straightened while the levers 17 remain stationary.

15 After a rivet has been set and the mandril severed, the tool will be removed from the work and the handle 47 will be turned to release the portion of the mandril which is left in the tool. Immediately that mandril portion is released, the 20 spring 53 will operate the plunger 51 to eject the mandril portion or to move it into a position from which the operator can readily withdraw it.

The operation of the tool when the stop-screw 25 127 is operative is similar except that in this case the stop-screw 127 will occupy a position (such as that shown in Figs. 1 and 4) in which it serves to set a predetermined limit to the distance through which the mandril may be pulled with

30 respect to the rivet. Thus, in setting successive rivets of the same length in work of the same thickness with the same setting of the stop-screw 127 the mandrels will be pulled a uniform distance until the right-hand side (as looked at in Figs. 1 and 4) of the block 9 engages, and is stopped by, the stop-screw 127. The springs 121 then yield to permit further movement of the head 35 until it engages the screw 105 and causes operation of the cutters. The stop-screw

35 127 will be so adjusted that the stroke imparted to a mandril will be just sufficient to cause adequate setting of the rivet. With different thicknesses of work to be riveted, the stop-screw 127 may require to be set in different positions.

40 45 A rivet R which has been set by the use of the illustrative tool in accordance with either of the aforesaid methods is shown in Figs. 9, 10 and 11. It will be seen that the head H of the mandril

50 M has been drawn into the setting end portion of the rivet to expand the rivet and to cause the work to be firmly gripped between the head of the rivet and the expanded portion of the rivet. The portion of the mandril left in the rivet serves 55 to plug the bore of the rivet and considerably increases the shear strength of the joint. It will be observed in Figs. 9, 10 and 11 that the metal of the rivet at the setting end portion thereof not only has surrounded the head of the mandril but also somewhat contracted over the head of the mandril in a known manner. At the severed end of the mandril a fishtail F has been formed (see Figs. 9 and 10) of a width greater than the diameter of the bore in the rivet. This fishtail

60 65 F will therefore serve as a second head on the mandril portion and, together with the pre-formed head H, prevent the mandril portion from being dislodged from the rivet. The side of the severed end part of the mandril shown in Figs. 9 and 10 is that which has been engaged by the cutter 55 and the fishtail at this side has a recess (best seen in Fig. 9) indented by the point of the cutter 55.

70 In Figs. 9, 10 and 11 the severed end of the mandril portion is shown as projecting slightly

beyond the head of the rivet. Furthermore, the throat of the rivet has a slight flare in which the fishtail may be nested or countersunk by driving the mandril back to the position represented in Fig. 12. A light tap of a hammer will produce this result and will still leave the fishtail in a condition to retain the mandril in the rivet.

Having described our invention, what we claim as new and desire to secure by Letters Patent of the United States is:

1. A rivet-setting tool comprising means arranged to grip a portion of the stem of a rivet-setting mandril, means arranged to swage and sever the stem between said gripping means and a hollow rivet surrounding another portion of the stem, toggle means arranged to operate said swaging and severing means, a supporting structure by which said means are all maintained in assembled relation, and an actuating mechanism arranged to shift said gripping means and the knee of said toggle means successively and both lengthwise of the mandril to upset a rivet and swage the mandril.

2. A rivet-setting tool comprising means arranged to grip a portion of the stem of a rivet-setting mandril, means arranged to swage and sever the stem between said gripping means and a hollow rivet surrounding another portion of the stem, toggle means arranged to operate said swaging and severing means, a supporting structure by which said means are all maintained in assembled relation, a lazy tongs arranged to shift said gripping means in a direction to upset the rivet with collapsing movement of the tongs, and a striker carried by an intermediate portion of the lazy tongs for operating said toggle means with supplemental collapsing movement of the tongs after the rivet-upsetting component of such movement.

3. A rivet-setting tool comprising means arranged to grip a portion of the stem of a rivet-setting mandril, means arranged to brace the head of a hollow rivet surrounding the stem and sever the stem between the rivet and said gripping means, a supporting structure by which said means are maintained in cooperative relation, and an actuating mechanism arranged to shift said gripping means lengthwise of the rivet far enough to complete the upsetting thereof without bending the mandril or operating said severing means and thereafter to operate said severing means while continuing to stress the gripping means in the upsetting direction, said actuating mechanism including a yieldable connection that enables the mandril-gripping means to remain stationary while the severing means is in operation.

4. A tool as set forth in claim 2 in which the

lazy tongs includes a lost-motion connection that enables the mandril-gripping means to remain stationary while the tongs operate said toggle means.

5. A rivet-setting tool comprising means arranged to grip a portion of the stem of a rivet-setting mandril, means arranged to swage and sever the stem between said gripping means and a hollow rivet surrounding another portion of the stem, a supporting structure by which said means are maintained in assembled relation, an actuating member, means by which said actuating member is guided toward and from the work along a path extending lengthwise of the mandril, and means operable by travel of said actuating member toward the work for shifting said gripping means in the opposite direction to upset a rivet, said swaging and severing means being operable by further travel of said actuating member toward the work after completion of the rivet-upsetting component of such travel.

6. A tool as set forth in claim 2 in which the toggle means includes an adjustable member arranged to vary the location of the point in the path of said striker at which the latter becomes effective to operate the toggle means.

7. A rivet-setting tool comprising means arranged to grip a portion of the stem of a rivet-setting mandril, a pair of jaws provided with blunt nippers arranged to swage and sever the stem between said gripping means and a hollow rivet surrounding another portion of the stem, said nippers having one a point to indent and spread a portion of the mandril stem and the other having angularly related stem-engaging faces forming a notch in register with said point, a supporting structure by which said means and said jaws are maintained in assembled relation, and an actuating mechanism arranged to shift said gripping means and thereafter operate said jaws and thereby upset the rivet before closing said nippers.
